METALLIC SPOOL

Wallace C. Mills, Rockford, Ill., assignor to J. L. Clark Manufacturing Co., Rockford, Ill., a Corporation of Illinois

Application June 9, 1930. Serial No. 459,870

10 Claims. (Cl. 242—123)

The invention pertains to spools or reels of the type embodying a tubular body usually constructed of sheet metal and having a pair of heads each composed of one or more sheet metal plates and secured upon opposite ends of the body.

The primary object of my invention is to provide a spool of this character in which the heads are secured on the ends of the tubular body in a manner such as to lend strength and rigidity to the connection as well as to present a neat appearance.

A common method of fastening a spool head on the end of a tubular body consists in providing a circular series of lugs or tabs formed on the end 15 of the body and bent into engagement with a head plate to secure the latter in position. The present invention involves such a method of fastening a head on the tubular body, and a further and more specific object thereof is to improve this method of fastening by the provision 20 of an annulus bent into engagement with the fastening lugs so as to bind or clamp them firmly upon the head plate and at the same time entirely conceal the same.

The objects of the invention thus generally set forth, together with other and ancillary advantages are attained by the construction and arrangement illustrated in the accompanying drawing forming part hereof, wherein:

Figure 1 is a fragmentary side elevational view of a spool with one end portion shown in section to illustrate the construction employed.

Fig. 2 is a fragmentary transverse sectional view taken in the plane of line 2—2 of Fig. 1, being shown on a reduced scale.

Fig. 3 is an elevational view of one end of the body before the head is attached thereto.

Fig. 4 is a fragmentary sectional view illustrating a modified form of the invention.

Fig. 5 is a similar view illustrating another modification.

Fig. 6 is a plan view of a spacer ring employed in the form shown in Fig. 5.

The spool comprises a tubular body 7 having heads 8 secured at opposite ends thereof. The body 7 is formed from a flat sheet of metal bent into cylindrical form and cut at opposite ends to form tabs or lugs 9 spaced a short distance apart in a circular series. Each head comprises a circular plate or disk 10 having its peripheral edge curled as at 11. Spaced radially inwardly from said peripheral edge is a circular series of slots 12 adapted to receive the lugs 9.

The lugs 9 are of a length substantially greater than the thickness of the disk 10 so that when

the lugs are entered through the slots with the disk seated upon the end edges of the body formed between the lugs, the latter will project a substantial distance beyond the disk. The lugs are thus capable of being bent transversely of the body into engagement with the disk.

For the purpose of clamping the securing lugs 9 firmly upon the disk and at the same time concealing the lugs, the head is constructed to provide an annulus 13. This annulus in the embodiment shown in Fig. 1 is made integral with the disk 10 by forming therein an outwardly extending fold whose open end is disposed within and closely adjacent to the end of the body. The lugs 9 are thus disposed adjacent the outer leg 65 of the fold so that by bending the latter outwardly and downwardly toward the disk the lugs are bent flat upon the disk in underlying relation to the annulus.

An end closure plate 14 for the tubular body 75 comprises in this instance a disk formed integral with the annulus and hence with the disk 10. Thus the inner leg of the fold constituting the annulus may be extended inwardly to form the plate 14 which is centrally apertured to receive the end of an inner core 15 having its ends curled outwardly into engagement with said end plate.

I have found that the annulus thus provided serves effectually to bind the lugs 9 firmly against 85 the disk 10 so as to insure that the head shall be fastened securely on the end of the body with the lugs concealed from view to the end that the spool shall present a neat appearance.

In the embodiment illustrated in Fig. 4, the 90 head comprises a circular plate or disk 10' and a separately formed end closure plate 14'. The disk 10' terminates in a flange 16 within and concentric to the end of the body, and an annulus 13' is in the form of a fold formed integral with the plate 14'. The annulus in this instance receives both the lugs 9 and the flange, so that the free edge of the annulus is curled around the flange 16 and interlocked between the lugs and the disk 10' at a point adjacent the 95 body 7. The end closure plate 14' may be centrally apertured to receive the end of an inner core 15' as in the case of the form shown in Fig. 1.

As shown in Fig. 5, the invention is applicable 105 also to a spool construction in which the head comprises a face plate 17 and a backing plate 18 separated at a point adjacent the body by a spacer member in the form of a ring 19 encircling the body, notches 20 being cut in the ring to re- 110

ceive lugs 9'. An annulus 13^a is formed integral with the face plate 17 in a manner similar to the annulus 13 (Fig. 1), and this plate is extended inwardly to form an end closure plate 14^a as in the construction shown in Fig. 1. The two plates 17 and 18 are fastened together at their peripheral edges by means of interengaging curls 20 and 21, and the backing plate 18 may have formed integral therewith a reinforcing plate 22 in the body 7. Thus the plate 18 may be extended inwardly into the body and centrally apertured to receive the end portion of the inner core 15^a which is interengaged at its extreme end with the end plate 14^a.

15. The double end wall provided in this instance results in a more rigid construction, especially when used in connection with the spacer ring combined with the clamping action of the annulus on the securing lugs 9'.

20. I claim as my invention:

1. A spool comprising a tubular body having a plurality of lugs projecting from one end thereof, and a head comprising a disk extending radially from said body and having a plurality of slots therein through which said lugs are adapted to pass, a second disk within the body and forming an end closure plate therefor, and an annulus formed integral with the slotted disk and bent outwardly upon said lugs with the latter disposed in transverse relation to the body.

25. 2. A spool comprising a tubular body having a plurality of lugs projecting from one end thereof, and a head comprising a disk extending radially from said body and engaging therewith so as to be held against movement in one direction axially of the body, a second disk within the body and forming an end closure plate therefor, and an annulus in the form of a fold disposed wholly to one side of said lugs and having one leg formed integral with one of said disks, said annulus being bent upon said lugs in transverse relation to the body.

30. 3. A spool comprising a tubular body having a plurality of lugs projecting from one end thereof, and a head comprising a disk extending radially from said body and having a plurality of slots therein through which said lugs are adapted to pass, a second disk within the body and forming an end closure plate therefor, and an annulus in the form of a fold the opposed legs of which are respectively formed integral with the two disks and bent from a point within the body upon said lugs in transverse relation to the body.

35. 4. A spool comprising a tubular body having a plurality of lugs projecting from one end thereof, and a head for the spool comprising a pair of disks encircling the body and each having a series of slots through which said lugs are adapted to pass, and an annulus formed integral with one of said disks and bent radially outwardly from a point within the body into overlying relation to said lugs transversely of the body.

60. 5. A spool comprising a tubular body having a plurality of lugs projecting from one end thereof, and a head for the spool comprising a pair of disks encircling the body, the innermost one

of said disks engaging the body so as to be held against axial movement thereon in one direction, and an annulus formed integral with one of said disks and bent radially outwardly from a point within the body into overlying relation to said lugs transversely of the body, and an annular spacer member interposed between said two disks adjacent the body.

65. 6. A spool comprising a tubular body having a plurality of lugs projecting from one end thereof, and a head comprising a pair of disks encircling the body with said lugs extending therethrough, a closure plate for the body, and an annulus in the form of a fold the opposed legs of which are respectively formed integral with one of said disks and said closure plate, said annulus being bent upon said lugs in transverse relation to the body.

70. 7. A spool comprising a tubular body having a series of lugs projecting from one end thereof, and a head for the spool comprising a disk having a series of slots therein through which said lugs project with a portion of the disk extending inwardly beyond the slots and bent reversely to form an annulus disposed in overlying relation to said lugs with the latter extending transversely relative to the body.

75. 8. A spool comprising a tubular body having a series of lugs projecting from one end thereof, and a head for the spool comprising a disk having a series of slots therein through which said lugs project with a portion of the disk extending inwardly beyond the slots and shaped to form an annulus in the form of a fold of substantial depth, said lugs being bent outwardly in transverse relation to the body and said annulus being bent outwardly into clamping relation with said lugs with the bight of said fold forming an outer rounded edge for the annulus.

80. 9. A spool comprising a tubular body having a plurality of lugs projecting from one end thereof, and a head comprising a disk extending radially from said body and having a plurality of slots therein through which said lugs are adapted to pass, a second disk within the body and forming an end closure plate therefor, said first disk having a portion extending beyond said slots and bent reversely upon said lugs in transverse relation to the body, and said second disk having a part formed integral therewith bent into overlying relation to said bent portion of the first disk.

85. 10. A spool comprising a tubular body having a plurality of lugs projecting from one end thereof, and a head comprising a disk extending radially from said body and slotted to receive said lugs, a separately formed second disk within the body and forming an end closure plate therefor, said first disk having a portion extending beyond said slots and bent reversely upon said lugs in transverse relation to the body, and said second disk having a part bent into overlying relation to said bent portion of the first disk and curled around the same to form a smooth rounded surface.

90. WALLACE C. MILLS.
